UNITED STATES PATENT OFFICE

EMANUEL J. WOERNER, OF CHICAGO, ILLINOIS

PAPER-HANGER'S STRAIGHTEDGE

Application filed December 1, 1928. Serial No. 323,042.

This invention relates to paper-hangers' straight edges and has for its primary object the construction of such devices from metal, preferably of duraluminum or stainless steel, thereby causing them to be unaffected by heat or humidity and preventing them from warping or otherwise becoming unsuitable for proper and efficient use.

Another object of this invention is the production of straight-edges of the character set forth, each of which consists of a primary and an auxiliary member, which are so assembled that the auxiliary member will at all times reinforce and brace the primary member, whereby the straight-edge will be true at all times.

Another object of this invention is the construction and assembly of the straight-edges so that the auxiliary member will fit within the primary member, whereby the primary member will be provided with protruding edges, thereby forming cutting edges and permitting the straight-edge, when in use, to lie evenly its entire length.

A still further and important object of this invention is the production of straight-edges possessed of the foregoing advantages and which are yet formed of a minimum number of parts, and therefore, may be produced at a minimum expense.

With the foregoing and similar objects in view, this invention consists of certain combinations, arrangements and assembly of parts, as will be more fully set forth herein and will be fully illustrated in the drawings, wherein like reference numerals will indicate like parts in the several views, in which

Fig. 1 is a bottom plan view of another embodiment of the present straight-edge, parts thereof being broken away;

Fig. 2 is a transverse sectional view through this embodiment of the straight-edge, taken on the line 2—2 of Fig. 1;

Fig. 3 is a top plan view of still another embodiment of the present invention, parts thereof being broken away; and

Fig. 4 is a transverse sectional view of this embodiment of the straight-edge, taken on the line 4—4 of Fig. 3.

Referring more particularly to the draw-

ings, the straight-edge includes the primary member "A" having the back 1 and the walls 2 having the cutting edges 3. The auxiliary member B' however, consists of a narrow elongated back 9 having formed along its side edge portions the webs 10, these webs 10 extending outwardly and angularly from the back 9, as clearly illustrated in Fig. 2. The inwardly extending narrow walls 11 are formed along the outer edge portions of the webs 10.

When this form of the straight-edge is assembled the auxiliary member B' will fit within the primary member "A". At this time the back 9 will engage the inner surface of the back 1 and the two backs are secured together by any suitable means, such as spot-welding, as shown at 12. Thus the primary member and the auxiliary member will be fixedly held together to present a rigid unitary construction. The angle of the webs is such as to cause the junction of the webs 10 and the walls 11 to be contiguous to but spaced from the cutting edges 3 of the walls 2.

In this structure shown in the drawings it will be seen that only two elements are necessary, the primary member and the auxiliary member. The auxiliary member will be entirely within the confines of the primary member, as clearly illustrated in Fig. 2 and for this reason will not interfere with the proper use of the primary member A. The formation of the auxiliary member B' will greatly reinforce the primary member, since the webs 10 are comparatively short in cross section and consequently are very rigid in their bracing action near the edges 3 of the walls 2. Pressure on the outer surfaces of the walls 2 will be resisted by the walls 11 of the auxiliary member, while contacting and securing together of the backs 1 and 9 will increase the rigidity and strength of the primary and auxiliary members. The inset construction of the auxiliary member B' will also permit the straight-edge to be easily gripped at all times.

Attention is now invited to the modification of my invention, as illustrated in Figs. 3 and 4. In this form the elongated back 13

has a wall 14 formed at one side edge portion thereof and this wall 14 extends at right angles to the back 13. At the other side edge portion the back 13 has an angular extension 15 and this extension 15 has the secondary back 16 projecting therefrom in a plane parallel to but spaced from the plane of the back 13. A narrow wall 17 is formed upon and extends at right angles to the secondary back 16. The wall 17 is parallel to the wall 14 but is narrower than the wall 14.

The auxiliary member D comprises a back 18 of rather narrow dimension and has extending from one side edge portion thereof the angularly extending web 19 which extends to a point near the edge 14' of the wall 14. The inwardly extending wall 20 is formed upon and extends from this outer edge portion of the web 19. A comparatively broad web 21 extends from the remaining side edge portion of the back 18 and this web 21 extends outwardly at an angle to the back 18 to a point near the edge of the wall 17, having formed thereon and extending inwardly 25 therefrom the wall 22.

When the primary member "C" and the auxiliary member D are assembled the back 18 will bear upon the back 13, while the wall 20 will bear upon the wall 14 and the wall 22 30 will bear upon the wall 17. The two members will be held in this assembled condition by any suitable securing means, preferably spot-welding as indicated at 23.

In this form of straight-edge an apron E 35 is provided. This apron consists of a supporting wall 24 having formed thereon and extending at right angles thereto the overhanging flange 25. The supporting wall 24 bears upon the outer surface of the wall 17 40 of the primary member C and is fixed in position by spot-welding, as indicated at 26. The edge 27 of the supporting wall 24 protrudes beyond the outer edge of the wall 17, while the opposite edge portion of the supporting wall 24 extends beyond the outer surface 45 of the secondary back 16, whereby the flange 25 will extend in the same plane as the back 13 of the primary member C. The flange terminates at a distance from the angular extension 15, thereby forming a longitudinally extending groove F which will accommodate a wheel knife or paper cutting device, when the straight-edge is in use.

The two modifications of the straight-edge 55 as herein described are very similar. They each consist of a primary member, within which the auxiliary member is permanently fitted for the purpose of reinforcing the primary member. Straight edges constructed 60 according to this invention are more durable than the wooden straight-edges now in use. They will not warp due to heat, humidity, or dampness, this latter objection resulting in the use of all wooden straight-edges.

The straight-edges of the present invention

are formed from sheets of metal, preferably duraluminum or stainless steel. Therefore, they are very light, the weight depending, of course, upon the sizes of the structures. The lengths and widths of the straight-edges of this invention may be increased or decreased as occasion demands, without departing from the spirit of the invention. Furthermore, although these straight-edges present very efficient structures for proper and ready handling and use, laying flat throughout their entire lengths when in use, their simplicity of construction permits of their construction and assembly at a minimum of expense.

While I have specifically described and illustrated two modifications of my invention, it is obvious that changes may be made in the detail construction and assembly without departing from the spirit of the invention as long as such changes do not exceed the scope of the invention as claimed.

Having described the invention, what I claim as new is:

1. A straight-edge of the character described comprising a primary member, said primary member including an elongated back having a wall extending from one side edge portion at right angles thereto, an angular extension protruding from the other side edge portion of said back, a secondary back carried by said angular extension in a plane parallel to said first-mentioned back, a wall carried by said secondary back in a plane parallel to said first-mentioned wall, an auxiliary member comprising an elongated back engaging the first-mentioned back of the primary member, webs extending angularly from the back of the auxiliary member, parallel walls carried by the outer edge portions of said webs, the walls of the auxiliary member engaging the walls of the primary member, an apron comprising a supporting wall and a flange, the flange extending at a right angle to the supporting wall, said supporting wall being fixed upon the wall of the primary member adjacent said angular extension, said flange overhanging said secondary back and terminating at a distance from the angular extension of the primary member, thereby forming a longitudinally extending groove, as set forth.

2. A straight-edge of the character described comprising a sheet metal primary member, said primary member consisting of an elongated back having parallel walls extending from and at right angles to its side edge portions, a sheet metal auxiliary member including an elongated back having webs extending from opposite sides thereof, parallel walls extending at acute angles to and being carried by the outer edge portions of said webs, the back of the auxiliary member engaging the inner surface of the back of

the primary member, means for holding the backs together, whereby the walls of the auxiliary member will engage the inner surfaces of the walls of the primary member, all as and for the purposes set forth.

5 In testimony whereof I affix my signature.

EMANUEL J. WOERNER.
